United States Patent Office.

PHILIP H. KELLS, OF ADRIAN, MICHIGAN.

Letters Patent No. 66,355, dated July 2, 1867.

IMPROVED BRICK MACHINE.

The Schedule referred to in these Letters Patent and making part of the same.

TO ALL WHOM IT MAY CONCERN:

Be it known that I, PHILIP H. KELLS, of Adrian, in the county of Lenawee, and State of Michigan, have invented certain new and useful improvements in Brick Machines; and I do hereby declare the following to be a full, clear, and exact description of the same, reference being had to the accompanying drawings, which are made part of this specification, and in which—

Figure 1 is a sectional elevation of a brick machine embodying my invention, the plane of vertical section being indicated by the lines $z z$, fig. 2.

Figure 2 is a top view of the same partly in section, the planes of horizontal section being indicated by the lines $y y$, fig. 1.

Figure 3 represents a vertical section on the line $z z$, fig. 2.

Similar letters of reference indicate corresponding parts in the two figures.

This invention relates to certain improvements in the brick machine for which Letters Patent, numbered 63,057, were granted to me on the nineteenth day of March, 1867.

One feature of the present improvement consists in the method of constructing the bed-plate for the reception of the pug-mills, said plate being of a single piece of metal, which is cast solidly with annular flanges, into which the lower ends of the cylinders or pug mills are inserted.

The invention also consists in the arrangement of a stationary plate, which sustains the pressure when the followers are made to act upon the clay, and which is formed with a sharp cutting edge, which occupies a position on the interior of the pug-mill at the point where the filled moulds pass from beneath the discharge aperture in the bottom of the said pug-mill, and which serve to shave or remove the superfluous clay from the moulds, and leave the same inside of the clay-mill or tub.

The invention also consists in adjustably supporting the bed-plate, so that from time to time, to compensate for wear on the frictional surface of the mould-wheel and bed-plate, it may be moved and set or held in closer proximity to the latter in order to prevent the clay from working out between the joints.

The invention further consists in a novel method of arranging and adjusting the inclines which elevate the followers to compress the clay in the moulds; constructing and applying a smoothing-knife and clay-guard; adjusting the rollers upon which the mould-wheel revolves, and arranging the gearing by which the mould-wheel is driven, all as will be hereinafter fully explained.

In the accompanying drawings, A may represent a suitable base or frame, upon which the several operating parts of the machine are mounted. B is a bed-plate, supported upon the pillars or posts C C, the upper ends of which are provided with screw-threads and fitted to the threaded sockets D D. By the rotation of the posts C the bed-plate B may be lowered so as to bring it snugly against the surface of the mould-wheel E, and thus prevent the clay from working out between the joints. This adjustment is made from time to time in order to compensate for the wear to which the frictional surfaces of the bed-plate and mould-wheel are subjected. The adjustment of the bed-plate may be effected by any other suitable means. The bed-plate B is cast in one piece and is formed solidly, and, in conjunction with the annular flanges B¹ B¹, which receive the lower ends of the pug-mills F F, and confine them in position upon the bed-plate B. Stay-rods F¹ F¹ and nuts f f are employed to hold the pug-mills firmly in position. G is a horizontal driving-shaft, which may be driven by a band upon the pulley G¹, and which communicates motion to the pug-mill shafts F² F² through the gearing G² G³ G⁴. The clay is agitated and worked to the proper consistency by the arms or blades F³ on the rotary shafts F² F², and is ejected through the discharge aperture H¹ at the bottom of each pug-mill F by the spiral wings F⁴. I I are vertical shafts, rising from either end of the bed-plate B, and rotated by the shaft G through suitable gearing G⁵ G⁶. The lower ends of the shafts I I carry gear-wheels I¹ I¹, which communicate a rotary motion to the mould-wheel E through the intermediate gear-wheels I² I², which mesh with the cogs on the periphery of mould-wheel E. The frame in which the driving-shafts have their bearings is erected upon the bed-plate B, and moves with the latter under the adjustment to which it is subject. J (see fig. 3) represents a plate, which is secured to the under side of the bed-plate B in proximity to the aperture H¹, through which the clay is forced from each of the pug-mills F into the moulds e of the mould-wheel E. Each of these plates J is formed with a sharp cutting edge, which rests upon the face of the mould-wheel E, and serves to shave off and remove the superfluous

clay from the top of moulds e , as the latter pass from beneath the aperture H^1 ; most of the superfluous clay is thus prevented from passing out of the pug-mills. As soon as a filled mould, e , reaches a point immediately beneath the plate J , the follower K of that mould is forced upward by the contact of its roller K^1 with the incline L , the clay being thereby firmly compressed between the follower K and plate J . The bar of metal upon which the incline L is formed is adjustable vertically by means of the rods M and nuts m , for the purpose of adapting the machine to be set from time to time to compensate for the wear which is due to friction. It will also be seen that while the clay is being subjected to the action of the follower K , the rods M serve to hold that part of the bed-plate, and thus relieve the supporting frame of undue strain. A knife, N , is employed in connection with each pug-mill to remove any superfluous clay which may project above the moulds e , when the latter have passed from under the bed-plate. As the filled moulds emerge from under the bed-plate and pass beneath the knife N , the latter removes whatever superfluous clay there may be at the top of the moulds, and the clay thus removed is prevented from getting upon that part of the wheel E containing the preceding moulds by the shield N^1 , which is a flat piece, secured edgewise to the knife N by means of the threaded rod n and nut n^1 at its outer end, and by the projection b^2 on the bed-plate at its inner end. The outer end of the knife N is held against horizontal displacement by means of the rod n , while the inner end of the knife abuts against the stud n^2 , which serves to properly retain the knife in position without fastening or attaching it to the bed-plate. The set-screw n^3 , together with the nut n^1 , serves to hold the knife N snugly in contact with the face of the mould-wheel E . Both of the longitudinal edges of the knife N are ground to an edge, so that when one side becomes impaired by use, a new cutting edge may be brought into requisition by simply turning the knife over. As the mould-wheel continues to revolve, the moulds e are successively carried under the knives N , as above described, and then the rollers K^1 move in contact with the stationary inclined planes O , and the bricks are ejected upward from the moulds.

The central support of the mould-wheel E may be similar to that shown in my patent previously alluded to; but in the present case it is represented as having two central bearings, $e^2 e^3$, instead of one as proposed in the previous patent. The wheels P , which afford bearing points for the wheel E near its outer rim or circumference, are each journaled in a metallic frame, P^1 , which is fulcrumed or adjustably supported upon the stationary base-plate P^2 , which is formed with vertical projections $p p$, for the lateral support of the frame P^1 , as clearly represented in fig. 2. The arm or limb p^1 of the frame P^1 , is held by a screw-bolt, p^2 , and nut p^3 , by turning which latter the frame P^1 may be vibrated after the manner of a lever, so as to force the wheels upward and hold them in proper position to afford the requisite bearing for the wheel E . The tendency of the pug-mill shafts, when in operation, is to force upward the horizontal girt R , which connects the ends of the shaft-supporting frames. I therefore propose to employ a stay-rod, Q , which, at its lower end, is tapped into the hub B^4 on the bed-plate B , or otherwise fastened thereto, and fastened at the upper side of said girt R by means of nut B^5 .

Having thus described my invention, the following is what I claim as new herein, and desire to secure by Letters Patent:

1. I claim the bed-plate B , formed with the annular flanges $B^1 B^1$, for the reception of the pug-mills $F F$, substantially as described.
2. I claim the cut-off plate J , arranged and operating in the manner and for the purpose specified.
3. I claim the bed-plate B when supported so as to be adjustable in relation to the mould-wheel, substantially as described.
4. I claim the adjustable incline L , arranged and operating in the manner and for the purpose explained.
5. I claim the reversible knife N , formed with cutting edges on its opposite sides, and arranged and applied to operate as set forth.
6. I claim the combination with the knife N of the clay-guard or shield N^1 , arranged and employed in the manner and for the purpose set forth.
7. I claim the combination, with the wheel P , of the adjustable supporting frame P^1 , stationary base-plate P^2 , projections $p p$, screw-bolt p^2 , and nut p^3 , substantially in the manner and for the object specified.
8. I claim the arrangement of the intermediate gear-wheels $I^2 I^2$, in connection with the mould-wheel E and cog-wheels $I^1 I^1$, as herein described and represented.

PHILIP H. KELLS.
